(57) **CLAIM**

The ornamental design for a push-up bar, as shown and described.

DESCRIPTION

FIG. 1 is a perspective view of a push-up bar;
FIG. 2 is a front elevational view thereof;
FIG. 3 is a rear elevational view thereof;
FIG. 4 is a right-side elevational view thereof;
FIG. 5 is a left-side elevational view thereof;
FIG. 6 is a top plan view thereof;
FIG. 7 is a bottom plan view thereof; and,
FIG. 8 is a perspective view thereof wherein a person is in position to perform a push-up using a particular hand grip.
The broken line showing of a person in FIG. 8 is included for the purpose of showing environmental structure and forms no part of the claimed design.
